UNITED STATES PATENT OFFICE.

JOHN C. BARCLAY, OF NEW YORK, N. Y.

TELEGRAPH-SOUNDER.

SPECIFICATION forming part of Letters Patent No. 734,453, dated July 21, 1903.

Application filed March 24, 1903. Serial No. 149,271. (No model.)

To all whom it may concern:

Be it known that I, JOHN C. BARCLAY, a citizen of the United States, residing at New York, in the county of New York and State of New York, have invented certain new and useful Improvements in Telegraph-Sounders; and I do hereby declare the following to be a full, clear, and exact description of the invention, such as will enable others skilled in the art to which it appertains to make and use the same.

My invention relates to improvements in telegraph-sounders, and particularly to that type of sounders known as "box-relays," which are intended to be used in the main-line circuit.

My invention consists in the novel construction of the resonance-box, whereby the quality of the sound is improved and the adjustment of the instrument facilitated.

The objects of my invention are to improve the quality of the signals produced by box-relays and similar sounders, to make the sound produced thereby sharp and distinctive, to facilitate the adjustment of the magnets and the removal thereof, and to make the instrument simple, compact, sensitive, and neat in appearance.

I will now proceed to describe my invention with reference to the accompanying drawings and will then point out the novel features in claims.

In the said drawings, Figure 1 shows a side elevation of my improved box-relay or sounder. Fig. 2 shows a central longitudinal section of the instrument. Fig. 3 shows a rear view of the instrument. Fig. 4 shows a front view thereof, the spring-adjusting rod and the post therefor being omitted. Fig. 5 illustrates another device for limiting the motion of the magnet which may be employed.

It is frequently desirable in telegraph-work to locate a sounder in the main line and not in a secondary local circuit, as is the customary practice. By so doing the use of a main-line relay in addition to the sounder and the local circuit and its battery-cells is avoided, and this amounts in the aggregate to a very

great saving in expense, both in first cost and in maintenance. Main-line sounders heretofore used have been in substance large and heavy main-line relays, which, because of the weight of their moving parts, are sluggish. These large and heavy main-line sounders are also expensive.

In order to use the ordinary main-line relay as a sounder, its magnet has been inclosed in a resonance-box completely surrounding the magnet, resting at the bottom on the wooden base of the instrument, and carrying at one end the anvil, with which the armature co-acts, and at the other end carrying a bearing-piece for the magnet-adjusting screw; but the quality of sound produced by such instruments known as "box-relays" has not been such that such instruments could be used to any considerable extent as main-line sounders. Moreover, it is somewhat difficult to remove the magnets from such an instrument, as is necessary occasionally, since the magnets can only be removed by removing the resonance-box.

I have discovered that by making the resonance-box relatively shallow, so that it incloses a portion only of the magnet, by causing the box to rest upon the wooden base of the instrument at certain points only, by providing suitable sound-holes, and preferably by making the resonance-box, except that end thereof which carries the anvil, of metal, the said end being of wood, the quality of the signals produced by the instrument is much improved, and it is possible to use such instrument successfully as a main-line sounder without using magnets which are larger than those of the ordinary main-line relay.

Referring now to the accompanying drawings, the instrument there shown comprises the usual wooden base 1, magnet 2, adjusting-post 3, adjusting-screw 4, secured to the rear yoke of the magnet, adjusting-spring 5, and knurled head or nut 6 on the screw. It also comprises a trunnion-bracket 7 and an armature 8 pivoted thereto. This armature is of somewhat heavier construction than the armature of an ordinary main-line relay in

order to adapt the instrument for use as a sounder. The instrument is also provided with the usual post 9, carrying the spring-adjusting bar 10 and a screw 11 for adjusting the retractile spring. (Not shown.)

The resonance-box, in which my invention particularly resides, comprises a box-frame 12, preferably of metal, covering and inclosing the magnet for about one-half of its length. 10 The front of this box is a wooden diaphragm 13, secured to the box-frame 12 at its corners and carrying the anvil 14, which the armature 8 is arranged to strike. This diaphragm also carries the bracket 15 for the back-stop 15 16 of the instrument. The box-frame 12 rests on the wooden base 1 at its corners only, being provided with openings 17 at the sides and back, which in addition to confining the contact between said frame and the base to 20 the corners only serve as sound-holes. The diaphragm 13 is provided with a similar opening 18 at its bottom, so that it rests against the base at the corners only. The openings in the back of the box through which the 25 coils of the magnet pass are slightly larger than the coils, thereby permitting free vibration and escape of the sound-waves. The cores 20 of the magnet project through openings in the diaphragm 13 and are supported 30 by said diaphragm. A stop-shoulder 21 on screw 4 is provided to limit the forward motion of the magnet. The pivotal point of the armature is such that when the magnet is in contact with its stop and the armature is in 35 contact with its front stop said armature is vertical and in close proximity to but not in contact with the poles of the magnet. This resonance-box may be considered to be a drum, of which the box-frame 12 is the barrel 40 and the diaphragm 13 the head. Because of the way this diaphragm is secured to the box-frame it is as free to vibrate as is a drum-head. Because of this, because the said diaphragm and the box itself rest on the base at 45 the corners only, because ample openings are provided for the escape of the sound-waves, and also probably because the resonance-box is relatively shallow as compared with the boxes of box-relays heretofore used, since it 50 incloses a portion only of the magnet, the signals produced by this instrument are very clear and sharp and are quite loud. This makes it possible to use magnets of the same size and resistance as ordinary main-line relays and to make the instrument itself in size 55 and general construction similar to ordinary main-line relays. In addition to serving as a sounder this instrument may serve as a relay, the anvil 14 forming a front contact and, 60 if desired, the rear stop 16 being also a contact.

To remove the magnet, it is not necessary to remove the box, as in former box-relays. Instead the screw holding the post 3 in place

is unscrewed and said post lifted. The magnet may then be withdrawn without difficulty.

In Fig. 5 I show another construction for limiting the motion of the armature, which may be employed in lieu of that shown in Figs. 1 and 2. The adjusting-post 3 carries 70 a stop-pin 22, working in a slot 23 in screw 4. When the end of the slot comes into contact with this stop, the motion of the pin will be checked.

It is obvious that my invention is susceptible of various modifications in form and construction of the resonance-box, and I do not limit myself to the particular form of instrument illustrated and described.

In the following claims the term "relay" 80 is used in a generic sense.

In another application for Letters Patent, filed March 24, 1903, Serial No. 149,270, I have claimed the use of a stop for limiting the motion of a relay-magnet, so as to avoid contact 85 of the magnet with the armature.

What I claim is—

1. In a relay, the combination with a magnet and an armature therefor, of a resonance-box surrounding and inclosing that end of 90 the magnet nearest the armature, the opposite end of the magnet projecting from the box, an anvil carried by the resonance-box, and an armature-stop.

2. In a relay, the combination with a magnet and an armature therefor, of a resonance-box surrounding and inclosing that end of 95 the magnet nearest the armature, the opposite end of the magnet projecting from the box, an anvil carried by the resonance-box, 100 and means located outside of said box for moving the magnet toward and from its armature.

3. In a relay, the combination with a base, a magnet, an armature, an adjusting-screw 105 secured to the magnet, an adjusting-post supported by the base and supporting said screw, and means on said screw for moving the magnet toward and from its armature, of a resonance-box surrounding and inclosing the end 110 of the magnet nearest the armature, the other end of said magnet projecting from said box, an anvil carried by the resonance-box, and an armature-stop.

4. In a relay, the combination with a base, 115 a magnet, and an armature, of a resonance-box comprising a metallic box-frame closed at one end by a wooden diaphragm or vibrator arranged to be struck by said armature, said box supported by the base at certain 120 points only and having sound-openings between the points of support.

5. In a relay, the combination with a base, a magnet, and an armature, of a resonance-box comprising a metallic box-frame closed 125 at one end by a wooden diaphragm or vibrator, provided with an anvil arranged to be struck by said armature, said box supported

by the base at certain points only and having sound-openings between the points of support.

6. In a relay, the combination with a magnet, and an armature arranged to vibrate toward and away from the magnet, of an adjusting-post, an adjusting-screw passing therethrough and connected to the magnet, for adjusting the position of the magnet with

respect to its armature, and a nut, said screw provided with a fixed stop limiting the motion of the magnet toward its armature.

In testimony whereof I affix my signature in the presence of two witnesses.

JOHN C. BARCLAY.
